United States Patent Office

Des. 195,550
Patented July 2, 1963

195,550

GOLF CAR

Duncan McRae, Whitehall, Mich., assignor, by mesne assignments, to Chamberlin Metal Products Co., Frankfort, Mich., a corporation of Illinois

Filed June 6, 1962, Ser. No. 70,431

Term of patent 14 years

(Cl. D14—3)

Fig. 1

Fig. 2

FIG. 1 is a perspective view of a golf car, showing my new design from the front; and

FIG. 2 is a perspective view taken from the opposite side and rear.

The dominant features of my design reside in the portions shown in full lines.

I claim:

The ornamental design for a golf car, as shown and described.
